UNITED STATES PATENT OFFICE.

HENRY J. MERLE, OF CHICAGO, ILLINOIS.

SCHOOL DESK AND SEAT.

1,261,049.

Specification of Letters Patent.

Patented Apr. 2, 1918.

Application filed March 15, 1915. Serial No. 14,298.

To all whom it may concern:

Be it known that I, HENRY J. MERLE, a citizen of the United States, residing at Chicago, in the county of Cook and State 5 of Illinois, have invented certain new and useful Improvements in School Desks and Seats, of which the following is a specification.

My present invention relates in general to 10 school furniture and has more particular reference to the desks and seats, and more especially to the supporting means therefor.

One of the primary objects of this invention is to provide a supporting standard for 15 a school desk which will be strong and durable in construction, neat and attractive in appearance, and which, by reason of the elimination of all corners and sharp projections will preclude an accumulation of dust, 20 dirt, germs, etc., so that the desk will be thoroughly hygienic.

Another object of the invention is to provide a desk which can be vertically adjusted to any desired height, and one in which the 25 standards do not extend into the book box, and which is constructed to limit the raising movement of the desk so that it is impossible to accidentally separate the adjustable parts by raising the desk top too high.

30 A further object is to provide simple and highly efficient means for securing the desk in any desired vertically adjusted position, which is entirely inclosed within the structure of the standards where it can not be manipulated or tampered with by the pupils.

Still another object is to provide a desk standard which shall be entirely of tubular construction, thereby affording the greatest 40 strength with a minimum amount of material and also effectually sealing the standard against the entrance of dust, dirt and moisture, such as would attack the metal of the standard and also make it unsanitary.

Other objects and advantages of this invention will be readily appreciated as the same becomes better understood by reference to the following description when considered in connection with the accompanying drawings. Referring to the drawings—

50 Figure 1 is a perspective view of a school desk and seat embodying my invention;

Fig. 2 is a fragmentary vertical sectional view taken through one of the standards;

Fig. 3 is a cross sectional view taken on 55 the line 3—3 of Fig. 2;

Fig. 4 is a horizontal sectional view on the

line 4—4 of Fig. 2, the parts being shown in loosened position to permit adjustment of the desk;

Fig. 5 is a similar view showing the position of the parts when the standard is locked in adjusted position;

Fig. 6 is a transverse sectional view of the seat standard taken on the line 6—6 of Fig. 7;

Fig. 7 is a longitudinal sectional view taken on the line 7—7 of Fig. 6, and

Fig. 8 is a fragmentary sectional view showing the structure and manner of attachment of one of the standard feet.

The desk top, designated generally by reference character 9 in Fig. 1, comprises the book box 11 and the top proper or working surface 12. In many adjustable desks employed prior to my present invention the standards projected upwardly into the book box varying distances, depending upon the height to which the top was adjusted. In my present invention I have eliminated this objectionable feature by attaching the standards to the bottom 13 of the book box from which they extend downwardly, as shown in Fig. 2.

A plate 14 screwed to the bottom of the box has rigidly attached thereto a pair of 85 tubular members 15 and 16, respectively, which extend downwardly in parallel relation a considerable distance below the box. Intermediate their ends the tubes are braced and held in spaced relation by a tubular 90 cross-piece 17 equipped at its ends with blocks 18 and 19 shaped to conform to the opposed faces of the tubes 15 and 16.

These tubes 15 and 16 form the upper portion of the adjustable standards, the lower 95 portions of which consist of a pair of tubes 21 and 22 proportioned to telescope within the tubes 15 and 16, the tubes 21 and 22 being rigidly connected together by a tubular cross member 23. The lower ends of the 100 tubes which are bent outwardly in opposite directions, as shown in Fig. 1, are equipped at their lower ends with iron feet or bases 24. These feet, as shown in Fig. 8, are shaped to fit within the standards so that to 105 outside appearances they form a continuation of the standards and are apparently integral therewith, thus presenting a neat and attractive appearance to the lower end of the standard. The feet are preferably 110 acetylene-welded to the standard so as to be permanently and rigidly associated there-

with and are shaped to present an extended bearing surface to the floor, and are provided with screw holes by means of which the standards may be screwed to the floor. 5 These feet or bases are made of iron which does not rust and corrode as readily as steel, and they therefore provide not only a strong and durable base for the standards but also 10 hermetically seal the lower ends of the tubes to prevent moisture from flushing up into the hollow tubing, thereby prolonging the life of the tubes and at the same time rendering them entirely sanitary.

For the purpose of locking the telescoping tubes in any desired vertically adjusted position I have provided a simple and efficient locking mechanism which will now be described. The outer tubes 15 and 16 are provided in their inner walls with apertures 20 25 and 26, respectively, disposed in axial alignment with the blocks 18 and 19 and are provided in their outer walls with vertically elongated openings 27 and 28 through which the shanks of the blocks 29 and 31 25 extend. The tubes 21 and 22 are provided with aligned longitudinally extending slots 32 of sufficient width to accommodate the shanks of the blocks 29 and 31. Within the tubes 21 and 22 are disposed blocks 33 and 30 34 which are carried by a bolt 35 passing transversely through the standard, as shown in Figs. 2, 4 and 5. The block 29 is carried by the head end of the bolt with its shank 35 projecting through the elongated opening 27 of the outer tube and the slot 32 of the inner tube, the inner end of the shank 29 abutting against the block 33. The shank of block 31 projects inwardly through the opening 28 and the corresponding slot 32 40 into engagement with the inner block 34. A nut 36 shaped to be engaged by a specially formed wrench is threaded upon the end of the bolt 35 outside the block 31. When the nut is loosened the parts assume substantially the positions shown in Fig. 4 and the desk top may be raised or lowered to the desired height. When the required height or approximately this height has been determined the nuts 36 may be tightened 45 slightly with the fingers sufficiently to hold the desk temporarily in position while permitting further vertical adjustment if necessary. Thereafter the nuts may be tightened up with the wrench until the standard is 50 firmly locked in the adjusted position. The tightening of the nuts draws the shanks of the blocks 29 and 31 against the inner blocks 33 and 34 thereby causing the inner side of the inner tubes to be clamped between the outer tubes and the respective inner blocks, 55 as shown in Fig. 5. It will be manifest that the clamping mechanism effectively holds the standard in adjusted position and that the working parts are entirely inclosed in 60 the standard construction where they can-

not be manipulated or tampered with by the pupils. Since the nuts 36 are practically round and can only be operated by a specially shaped wrench which is kept in the custody of some one in authority, the desks, when once adjusted for any particular pupil, cannot be manipulated or further adjusted except by the person having possession of the wrench.

It will also be manifest that the upper ends of the slots 32 in the inner tubes limit the upward movement of the desk top so that any liability of lifting the top off of the standards is precluded. The standards as described are strong and durable, neat in appearance, light in weight and are entirely closed so that dust, dirt or moisture cannot accumulate on the inside of them, and are also smooth on the outside, presenting no corners or crevices for the accumulation of dust or dirt, thus rendering the desk very sanitary for school purposes.

The desk is shown in elevated position in Fig. 1 in dotted lines as is also the seat 37 which is mounted for vertical adjustment 90 upon a standard similar in general structure to the desk standards, and which will now be described. Referring more particularly to Figs. 6 and 7 it will be observed that the seat proper is mounted upon the upper end 95 of a tubular member 38 adapted to telescope within a lower tubular member 39 fixedly mounted in an iron base 41. The member 38 is slotted longitudinally to permit vertical adjustment thereof, and a bolt 42 carries an exterior block 43, a wedge block 44 and a two-piece expansion ring 45. A nut 46 is threaded upon the end of the bolt and when this nut is tightened up the wedge-shaped shank of the block 44, extending 105 through an aperture 47 in the member 39 and through one of the longitudinal slots in the member 38, enters between the opposed ends of the expansion ring 45 and expands the ring thereby pressing outwardly on the 110 tube 38 so that the two tubes are firmly clamped together against relative vertical movement. It will be observed that one member of the expansion ring is provided 115 with a transverse groove 48 which insures at least three bearing points for the ring when expanded; namely, at the points 49, 51 and 52, thereby preventing rocking of the tube 38 within the tube 39 such as might occur if only two bearing points were afforded. For the purpose of covering the slots in the member 38 to prevent the entrance of dust and dirt into the standard I have mounted a tubular sleeve 53 loosely 120 within the member 38 so that it will slide up 125 and down relatively to the tube 38 and cover the slots irrespective of the vertical position of the seat. The seat may be adjusted by simply loosening the nut 46 in the same manner that the desk is adjusted 130

when the nuts 36 are loosened, and it will be obvious that the seat and desk may be adjusted independently of each other to accommodate them to the size of the pupil and to position the desk at the proper height with respect to the seat.

My invention and its mode of operation should be fully understood from the foregoing without further description and while 10 I have shown and described a preferred embodiment of the invention it should be manifest that various modifications in the structural details shown and described may be resorted to without departing from the 15 essence of the invention as defined in the following claims.

I claim:

1. A school desk, comprising a top and a standard for each end thereof, each standard 20 consisting of a pair of rigidly connected tubes forming the bottom of the standard, a second pair of tubes connected to the desk top and telescopically engaging said rigidly connected pair, a bolt extending transversely through all of said tubes, and means 25 operated by said bolt for clamping said tubes together in adjusted position.

2. A school desk, comprising a top and a standard for each end thereof, each standard 30 consisting of a pair of rigidly connected tubes forming the bottom of the standard, a second pair of tubes connected to the

desk top and telescopically engaging said rigidly connected pair, a bolt extending transversely through all of said tubes, and means 35 operated by said bolt for clamping said tubes together in adjusted position, said means comprising a rigid member disposed between and engaging the outer tubes, blocks arranged within said inner tubes and 40 devices carried by said bolt for forcing said blocks toward said member.

3. A school desk, comprising a top and a standard for each end thereof, each standard consisting of a pair of rigidly connected 45 tubes forming the bottom of the standard, a second pair of tubes connected to the desk top and telescopically engaging said rigidly connected pair, a bolt extending transversely through all of said tubes, and means operated by said bolt for clamping said tubes 50 together in adjusted position, said means comprising a rigid member disposed between and engaging the outer tubes, blocks arranged within said inner tubes, and devices 55 carried by said bolt and projecting through the walls of said tubes into engagement with said blocks for forcing the blocks toward said member.

HENRY J. MERLE.
